UNITED STATES PATENT OFFICE.

NORMAN CROSLAND AMPT, OF ST. KILDA, VICTORIA, AUSTRALIA.

STRETCHER AND THE LIKE.

1,150,008.

Specification of Letters Patent.

Patented Aug. 17, 1915.

Application filed August 28, 1914. Serial No. 859,101.

To all whom it may concern:

Be it known that I, NORMAN CROSLAND AMPT, a subject of the King of Great Britain and Ireland, &c., residing at St. Kilda, in the State of Victoria, Commonwealth of Australia, have invented certain new and useful Improvements in Stretchers and the like; and I do hereby declare the following to be a full, clear, and exact description of the invention, such as will enable others skilled in the art to which it appertains to make and use the same.

My invention relates to a stretcher or the like which is to be suspended for use, and which can be collapsed to occupy small space, for portability, or to allow the saved space to be used. The parts can be readily disassembled, and a number of them are interchangeable. The stretcher can be suspended either indoors or in the open air, from any convenient support, as a ceiling, rafters, posts, trees, brackets, wall hooks or eyes, or so on.

This invention will be useful in barracks, hospitals, dwelling houses, and generally. The tension produced by suspension straps is such as to help to keep my stretcher taut, and provide for the taking up of stretching and bulging of the canvas or other material hereinafter termed the mattress. The stretcher has side rails and end rails and the latter are pivoted to one of the side rails. When in folded positions these end rails become longitudinal. The construction includes other details and may be according to the accompanying drawings, but is not limited thereto in minor respects. Various accessories known to be useful in connection with beds or stretchers may be added, and are not illustrated.

Figure 1 represents a perspective view of my stretcher with part broken away. Fig. 2 shows its rails which are seen to be, at one end, closed and strapped together. Figs. 3 and 4 are side elevations, and Fig. 5 is a plan view,—showing details which are explained later.

a, b, are the side or longitudinal rails.

c, d, are the end rails. The latter are connected pivotally to and under a side rail *a*, as by bolts *e, f*. The rail *b* rests on the end rails loosely but is kept in place by suspension means described later.

At its corners the stretcher rail ends over lap, some ends being marked *a¹, c¹*, and *b¹, e²*. Below each end of side rail *a* and the piv-

oted end rail, a space is formed by nuts, distance washers *c⁴*, or the like on respective pivot bolts *e* and *f*, for the purpose explained later.

A sheet mattress *g*, of canvas, or any suitable material as a foundation for bedding or to support an occupant or occupants, is connected in a suitable manner to the side rails, the sides of sheet *g* being, for example, looped to inclose these rails; this sheet is connected to the end rails as by adjustable straps *g³* passing through eyelets *g²* in sheet *g*. Cords *g⁴* or the like extend to a transverse piece *g⁵* when it is desired to keep pillows, or bedding from falling over the end of the stretcher.

I provide means to limit rotation of rail *b*; for example screw *g¹* through an eyelet in sheet *g*. This rail has at each end one or more stops *b⁴*, which thus retain about their normal positions, for a reason which will be apparent shortly.

The suspension means is shown as a combination of straps and cords. Thus the bases of cords *l, l¹* are shown above rail *a*, and the bases of cords *k, k¹* above rail *b*, and I provide these cords with means for length adjustment to regulate when required the height of the stretcher above the ground or floor. *j* are straps on hooks *j¹* which engage eyes of bolts *e, f*, and these straps engage D-rings or the like, which are engaged by eyes *j²* or the like at the bases of cords *l, l¹*. *j³* are sleeves, adapted to be pressed down to tighten cords *l, l¹* on the eyes *j²*. When raised these sleeves loosen the cords so that they can be adjusted to regulate the height of the stretcher.

Cords *k, k¹*, also have parts *j³, j²*, and D-rings as already described, and from the latter one or more straps (shown as two, *h, h¹*), extend downwardly in contact with the inner side and then the under side of rail *b*, and then outwardly to a suitable point of the end rail to which it is connected as at *c³*. I provide one or more suitable stops each of which may be a recess or a projection such as a flange, collar or as shown the pegs *b⁴* and each strap *h¹* may bear against a peg while it also presses the side rail outward (see Fig. 4) and pulls the end rail (see Fig. 5) so as to tend to stretch the mattress in the directions indicated by arrows. Should, therefore, there be a tendency by reason of weight on the mattress *g*, for rail *b* to be drawn

toward rail *a*, that tendency will evidently meet with resistance, and in practice I find that sheet *g* is kept taut enough for comfort, and is thus unlike ordinary stretchers. The stops *b*⁴ are located on the overlapping side rail *b* toward the ends thereof and beyond the end rails *c* and *d*, and act or serve as guiding means for directing the upward lead of the straps *h*¹, thus enabling a pulling force to be exerted on the end rails, and these stops further act as retaining or guarding means to keep the straps from being too easily detached.

To collapse the stretcher, the straps *h*¹ are moved clear of rail *b*, which I push up to rail *a*. These straps are disconnected from the parts above them, and then the two end rails can be swung under the rail *a*, and can be strapped as shown in part of Fig. 2. The space under rail *a* which is preserved by the distance members *c*⁴ then allows part of the sheet mattress *g*, when in collapsed position to be located between rail *a*, and the longitudinally set end rails.

It is not essential that the straps *h*¹ and the parts above them to which they are connected shall extend at those angles which happen to be illustrated. The means which prevent articles falling off the stretcher may be located between the suspension members on whatever ends or sides protection is desired.

Having described this invention, what is claimed by Letters Patent of the United States is:—

1. A stretcher or the like, having a pair of end rails and a pair of side rails, each end rail being pivoted to one of the side rails, suspending means for the pivoted ends of said end rails and their complementary side rail, and supporting straps or the like connected to the opposite ends of said end rails, and bearing against the

inner surface of the other side rail, so as to locate the latter, substantially as described. 45

2. A stretcher or the like, having a pair of end rails and a pair of side rails, each end rail being connected toward one end to one of the side rails, and the other of said side rails having its ends resting loosely upon and overlapping the free ends of said end rails, a mattress of foldable material secured to said rails; suspending means for the pivoted ends of said end rails and their complementary side rail, guiding means on said overlapping side rail, located toward the ends thereof and beyond said end rails, flexible members connected to said end rails toward the outer free ends thereof, and adapted to extend upwardly, in engagement with said guiding means, on the outside surfaces of said end rails and the inside surface of said overlapping side rail, and suspension means connected to the free ends of said flexible members, the whole operating to cause the overlapping side rail to be pressed and the end rails to be pulled to taunt the mattress when bearing weight, substantially as described. 65

3. In a stretcher a rail on one side having pivotal connections to end rails, and on the other side a rail resting on the end rails, suspension members connected to the end rails, stops for the said members on the side rail last mentioned, a mattress attached to the side rails and connected by adjustable means to the end rails, means to limit rotation of the side rail last mentioned, and connections between suspension members to prevent articles falling off the stretcher. 80

In witness whereof I have hereunto set my hand in the presence of two witnesses.

NORMAN CROSLAND AMPT.
